UNITED STATES PATENT OFFICE.

ARTHUR H. ADAMS, OF LA GRANGE, ILLINOIS.

PLAYING BALL AND METHOD OF MAKING SAME.

Application filed May 19, 1926. Serial No. 110,070.

This invention relates to new and useful improvements in playing balls and its object is the construction of a light, strong and resilient ball which has a limited trajectory and is therefore adapted for use in indoor golf games, tennis games and the like.

With this object in view, in accordance with the present invention, the air resistance of the ball is increased and its weight decreased by perforations or pores in its shell which communicate with the interior of the ball. Owing to the small amount of material used and the air friction produced by the perforations, the trajectory of the ball will

be limited regardless of its initial velocity. In order more clearly to describe the natures of the product and process forming the subject matter of the present invention, reference should be had to the drawings in which Fig. 1 is a perspective view of a ball; and Figs. 2 and 3 diagrammatically illustrate two stages of the manufacturing process.

Referring now to Fig. 1, we have a hollow playing ball the shell of which consists of two perforated hemispheres 1 and 2, the edges of which are cemented together at 3. The retiform shell may be a textile fabric, such as hexagonal mesh like a fishnet, or some inexpensive lace like net, a loose woven material like mosquito net, or a soft paper like Japanese mulberry paper. The mass of the fabric constitutes thicker threads or fibres with considerable open spaces between, thus obtaining a greater stiffness and more surface for air friction for equal mass than could be obtained if the material were thinner and more nearly imperforate. The perforations have a retarding effect on the ball causing it, in a sense, to sift through the air rather than part the air, and by reason of the many small air currents and eddies, exhausting the initial kinetic energy more rapidly than would be the case with a ball having an imperforate shell. The arrangement of the material in deeper ribs instead of in a uniform thinner shell makes greater strength, due to the law that the stiffness of beam is as the cube of its depth.

The shell is preferably stiffened with some hardening liquid or semi-liquid like cellulose nitrate or acetate, varnish or starch. Or, the network may be made of artificial

silk, the fibres of which, when treated by a solvent, break down and coalesce to form an integral but not quite imperforate hemisphere. The same result could also be obtained by an acid treatment of cotton fibres.

In accordance with the present invention the following method is used in the manufacture of such balls.

A small square of net fabric 4 is cut out and is dipped in a cellulose nitrate cement. It is left to dry until not quite stiff and is then stretched over the polished hemispherical end of a small metal rod 5 by forcing the rod through a hole 6 in another piece of metal 7 much after the manner of a drawing punch entering a drawing die forming drawn shells of material. The impregnated net is permitted to dry awhile before forming, because otherwise it would stick to the metal rod 5 and the hemisphere may be injured in loosening it. The fabric is permitted thoroughly to dry while held in the position illustrated in Fig. 3. Then the brass rod 5 is revolved, a cutting blade 8 being held against its protruding end carrying the net 4. The result is to cut off a hemisphere of stiffened fabric.

The edges of two such hemispheres are cemented together, preferably by holding the two hemispheres in suitable cages or fixtures. The cementing may be accomplished by dipping or spraying with a solvent such as acetone.

In order to minimize the danger of the net sticking to the brass rod 5, the latter may be nickel plated, waxed or oiled.

It will be obvious to those skilled in the art that many variations may be introduced in the choice of materials, mesh form and chemicals without departing from the spirit of the invention, and that the method herein described may also be varied within wide limits. The ball may, for instance, be constructed by wrapping on a wax ball strands of artificial silk, cementing together these strands with lacquer, and finally melting out the wax through a few pinholes, though this process is probably inherently more expensive.

What I claim is:

1. The method of making a light projectile of limited trajectory consisting in establishing an open work structure over a

- form, processing the structure to harden it in the shape of the form and removing the form from the hardened fabric.
2. A hollow playing ball formed of a thin shell of cellulose mesh.
3. A hollow playing ball formed of resilient mesh.
4. A hollow playing ball having a substantially retiform shell.
- 10 5. A hollow playing ball having a shell of stiffened mesh.
6. The method of making a light playing ball of limited trajectory consisting in impregnating a textile fabric with a stiffening material, forming the fabric into a hemispherical surface, hardening said stiffening material, and cementing together by their edges two similar hemispheres.
7. The method of making a light playing ball of limited trajectory consisting in impregnating a textile fabric with a stiffening material, partially drying the fabric, forming the fabric into a hemispherical surface, thoroughly drying the fabric, and cementing together by their edges two similar hemispheres.
8. The method of making a light playing ball of limited trajectory consisting in impregnating a textile fabric with stiffening material, forming the fabric over a hemispherical surface, hardening the stiffening material, removing the fabric from said surface, and cementing together by their edges two similar textile hemispheres.
- 20 9. The method of making a light playing ball of limited trajectory consisting in impregnating a textile fabric with a stiffening material, partially drying the fabric, form-
- ing the fabric over a hemispherical surface, thoroughly drying the fabric, removing the fabric from said surface, and cementing together by their edges two similar textile hemispheres.
10. The method of making a light playing ball of limited trajectory consisting in impregnating an openly woven textile fabric with a stiffening material, forming the fabric into a hemispherical surface, hardening said stiffening material, and cementing together by their edges two similar hemispheres.
11. The method of making a light playing ball of limited trajectory consisting in treating a loose woven fabric with a stiffening bath, stretching the fabric over a former, processing the treated and formed fabric to harden it in the shape determined by the former.
12. The method of making a light projectile of limited trajectory consisting in stretching an open woven fabric over a form, processing the fabric to harden it in the shape of the form, and removing the form from the hardened fabric.
13. The method of making a light projectile of limited trajectory consisting in forming a piece of open work fabric over a form, in stiffening the fabric in this shape by processing, in removing the form, and in cementing together by their edges a plurality of such stiffened and formed pieces of fabric.

In testimony whereof, I have signed my name to this specification, this twelfth day of May, 1926.

ARTHUR H. ADAMS.
